US00D879780S

(12) **United States Design Patent** (10) **Patent No.:** **US D879,780 S**
(45) **Date of Patent:** **** Mar. 31, 2020**

(54) **MULTI-FUNCTION CONVERTER**

(71) Applicant: **Gopod Group Ltd.**,
Shenzhen/Guangdong (CN)

(72) Inventor: **Zhuowen Liao**, Shenzhen (CN)

(73) Assignee: **Gopod Group Ltd.** (CN)

(**) Term: **15 Years**

(21) Appl. No.: **29/674,458**

(22) Filed: **Dec. 21, 2018**

(30) **Foreign Application Priority Data**

Dec. 6, 2018 (CN) 2018 3 0702384

Primary Examiner — Marie D. Fast Horse

(57) **CLAIM**

The ornamental design for a multi-function converter, as shown and described.

DESCRIPTION

FIG. 1 is a top view of a multi-function converter showing my new design;

FIG. 2 is a left side view thereof;

FIG. 3 is a right side view thereof;

FIG. 4 is a bottom view thereof;

FIG. 5 is a front view thereof;

FIG. 6 is a rear view thereof;

FIG. 7 is a top, front, left side perspective view thereof;

FIG. 8 is a top, front, right side perspective view thereof;

and,

FIG. 9 is a top, front, right side perspective view of the multi-function converter showing in FIGS. 1-8 in a stowed configuration.

The broken lines shown in the drawings illustrate portions of the multi-function converter that form no part of the claimed design.

1 Claim, 9 Drawing Sheets
